UNITED STATES PATENT OFFICE.

HARRIET M. CHITTENDEN, OF NEW YORK, N. Y.

GARMENT-PROTECTOR.

SPECIFICATION forming part of Letters Patent No. 290,319, dated December 18, 1883.

Application filed November 3, 1881. (No model.)

To all whom it may concern:

Be it known that I, HARRIET M. CHITTENDEN, of the city of New York, in the county of New York and State of New York, have invented a certain new and useful Improvement in Catamenial and Surgical Bandages, of which the following is a specification.

The nature and objects of this invention will fully appear from the subjoined description, when considered with reference to the accompanying drawings, in which—

Figure 1 is a front view of a figure having my improved bandage attached. Fig. 2 is a rear view of the same. Fig. 3 is a detached perspective view of my improved bandage.

A is a shield, made of any suitable non-absorbent or water-proof fabric or material, cut and made in saddle form. The upper back corner of said shield is lined with firm stiff cloth or material that renders it unyielding to the form. Said shield fits the lower part of the body and lower limbs of the wearer, and is designed to furnish a protection to the garments of females wearing it during the menstrual period, and as a surgical garment for either sex.

B is a waist-belt, made of webbing or any suitable material, and instead of fitting closely is made large enough so that the front and rear points droop and are arranged for attaching the straps which support the aforesaid shield. In the back part of said waistband is inserted a cross-piece of elastic webbing, C, for the purpose of rendering the belt self-adjusting, convenient, and comfortable to the wearer.

To the lower corners of the shield are attached bands D D, made of any suitable material, which may be entirely elastic, or partially of elastic webbing, as may be desired. These bands are for encircling the limbs of

the wearer, and serve to hold and retain the shield in place for the protection of the garments.

To the front and rear upper corners of said shield are attached straps b, made of suitable elastic or partly-elastic material, and are supplied with suitable loops, rings, hooks, or eyelets for securing said shield to the waist-belt. Said straps also have branch elastic straps d d, provided with clasps, by which any desired appliance, E, may readily and conveniently be attached and detached for the use of the wearer. The said straps d d have clasps for securing said absorber, by which the same may be readily attached or detached for the convenience of easily removing, cleansing, and replacing the absorber.

The peculiar advantages of this device are that it furnishes a perfect protection to the garments of the wearer, is convenient in applying, and is comfortable while worn.

I am aware that patents have been granted for bandages for the same purpose. I do not therefore claim, broadly, a bandage for this purpose; but

What I do claim is—

In a catamenial and surgical garment, the combination of the saddle-shaped shield A, of water-proof material, the adjustable straps D D, attached to its lower edges and passing around the thighs, the waist-belt B, with elastic cross-piece C, and pendent straps b b d d, for adjustably securing the shield A and pad E, all as described.

HARRIET M. CHITTENDEN.
